United States Patent Office.

A. W. JOHNSON AND GEORGE THOMPSON, OF NEW YORK, N. Y.

Letters Patent No. 64,880, dated May 21, 1867.

IMPROVEMENT IN PERMUTATION LOCKS.

The Schedule referred to in these Letters Patent and making part of the same.

TO ALL WHOM IT MAY CONCERN:

Be it known that we, GEORGE THOMPSON and A. W. JOHNSON, both of the city, county, and State of New York, have invented a new and useful Improvement in Locks, and that the following description, taken in connection with the accompanying drawings, hereinafter referred to, forms a full and exact specification of the same, wherein we have set forth the nature and principles of our said improvements, by which our invention may be distinguished from all others of a similar class, together with such parts as we claim, and desire to have secured to us by Letters Patent.

The present invention relates to that class of locks known as "combination locks," and the invention consists in a novel construction of the same, whereby simplicity of arrangement, effectiveness of operation, and security against being opened or unlocked when locked, by persons without authority, are obtained, as will be obvious from the following detail description of the same, reference being had to the accompanying plate of drawings, in which—

Figure 1 is a view of one edge of the lock-casing.

Figure 2, a central section through the thickness of the casing of the lock.

Figure 3, a view of the front plate of the lock-casing, showing the bolt and other parts dotted in; and

Figure 4, a view of the interior of the lock, with the front plate of the lock-casing removed.

A, in the drawings, represents the lock-casing, which in the present instance is made of a square shape, of suitable size to receive its various working parts; B, the front, and C the back plate of the lock-casing; D, the bolt, which, by its straight portion E, plays through the top or end-piece F of the lock-casing, from which, extending by its circular-shaped yoke-portion G, into the lock-casing, it plays, by its inner forked end H, upon a fixed stud or pin, I, of the lock-casing; J, a projection on one side or edge of bolt-yoke G, over which, as the bolt is moved in or out, as will be hereinafter described, plays the loose end K of a bent spring, L, secured at its other end to the lock-casing, this spring acting to hold the bolt either in or out, as the case may be, by being on either one or the other of the shoulders *a* of the projection J, as the case may be; M, a series of flat circular-shaped disk-tumblers, of uniform diameter and thickness, which disks are placed one upon another, in and between the sides of the yoke-frame G of the lock-bolt, as plainly shown in fig. 4 of the drawings. Each disk-tumbler M is similarly notched at one point of its periphery, one of which notches, N, is shown in fig. 4; and, for a purpose to be hereinafter described, one notch of the said disks is extended in length, as indicated by dotted lines at *b* in fig. 4. To each disk-tumbler M a tube, O, is connected, each of suitable internal and external diameter to fit one over and about the other, as illustrated in section in fig. 2 of the drawings, forming a series of concentric tubes, which pass through the front plate. The outer ends of the tubes O are similarly provided with teeth, *c*, the tubes being of unequal lengths, with the inner one of the series the longest, and the outer one the shortest, and with the said teeth *c* of each tube, the toothed edge or flange *d* of a series of rings, Q, engage, the one with the outer tube, and the two others with the inner and intermediate tubes. These rings Q fit one over the other, as shown in fig. 2 of the drawings, where, by means of a spindle or rod, R, passing loosely through the centre tube, with a head, S, at one end, and a screw-nut, T, at the other, they are held, while at the same time they can be freely turned, and through the engagement of their teeth with those of the tubes, the disk-tumbler correspondingly turned. The periphery of each ring of the series of rings is marked off into a series of divisions, with the division lines of the several rings occupying such relative positions that no two of any two of the series can coincide at any one time; W, a catch-lever, hung upon one side of bolt-yoke G, which lever, by its spring X, is forced to bear against the edge of the disk-tumblers, so that, when the notches of such disks all coincide, it will engage therewith, and thus, if the tumblers are then turned, cause the bolt to be thrown in or out, as the case may be. With a lock of the above-described construction and arrangement of parts, it is plain to be understood, that, to lock and unlock the lock, the notches of the disk-tumblers are required to coincide, so as to allow the proper connection to be established between them and the bolt to produce the desired inward or outward throw of the bolt, as the case may be. The bringing together of these notches is accomplished through the graduated rings, by turning them in the proper direction therefor, or, in other words, setting them so that certain ones of their divisions will coincide, for facilitating which the several divisions or graduations are lettered as shown in the drawings, fig. 1. To break the interlocking of the catch-

lever with the tumbler-disk, such lever is lifted out of the same by turning in the proper direction that tumbler-disk which has its notch extended, when then turning the other tumblers the adjustment is obviously broken, whereby the lock cannot then be changed, that is, locked if unlocked, or unlocked if locked, without the proper adjustment of the notches has first been made. In conclusion, it may be here observed that the catch-lever, as it enters the notches, owing to the spring which forces it, necessarily produces a clicking sound, by which, were nothing adopted to disguise it, the necessary adjustment of the disk-notches might by chance be made, and, therefore, to obviate all possibility of the lock thus being unlocked, we deem it best and advisable to notch, at different points, the edges or peripheries of the disk-tumblers sufficiently, that, while such notches will not allow the catch-lever to thus become engaged with the tumblers, it will occasion a similar clicking sound to that produced by the lever-catch as it drops into the notches, thereby, as is evident, serving as a "blind" to any person attempting to unlock it.

We claim as new, and desire to secure by Letters Patent—

The adjustable tubes O, of unequal length, fitting over each other, their outer ends provided with teeth c, which fit into corresponding teeth in the flange d of the graduated adjustable rings Q, fitting one within the other, the said tubes provided upon their inner ends with notched disks M, the notches in the outer ring being bevelled upon one side, when all are constructed and arranged as described, and operating upon the yoked-shaped bolt G, provided with the spring-pawl W, substantially as described, for the purpose specified.

A. W. JOHNSON,
GEORGE THOMPSON.
